DOUBLE HEAD HEMMING MACHINE

Joseph Galkin, New York, N. Y.

Application April 14, 1939, Serial No. 267,805

3 Claims. (Cl. 112—155)

This invention relates to double-head hemming machines designed to feed in the same direction for making two parallel lines of stitching simultaneously.

An object of this invention is to produce an efficient and practical double head sewing machine for simultaneously sewing two parallel rows of zig-zag stitches at the opposite edges of a piece of fabric.

Another object of this invention is to mount the two sewing machines on a table having a drive-shaft rearward of the sewing machines and to provide means whereby each of said machines may be swung above the table for bringing the normally concealed mechanism below the sewing machine base into fully accessible position.

Another object of this invention is to provide an external belt drive for driving the main shaft of the sewing machine from the said rearwardly positioned drive-shaft and so that the said belt drive will remain operatively connected during the swinging motion.

Another object of this invention is to provide each sewing machine with a lever actuated shears mounted on the base of and integral with the sewing machine and having a chain passing through the base of the sewing machine and engaging one end of the lever for actuating the shears from below the slideway.

Another object of this invention is to provide spring-pressed latching means for automatically locking each sewing machine in its rearward angular position above the slideway.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of a double head sewing machine embodying the invention.

Figure 2 is a plan view of the invention.

Figure 3 is a cross-sectional view, the section being taken as on line 3—3 in Figure 2 and showing the sewing machines in operating position on the slideway.

Figure 4 is a cross-sectional view similar to Figure 3 and showing one of the sewing machines swung about the drive-shaft as an axis and in angular relation with the slideway.

Figure 5 is a perspective view of a shear used for cutting the thread of one of the sewing machines.

Figure 6 is a fragmentary cross-sectional view, the section being taken as on line 6—6 in Figure 2.

In the illustrated embodiment of the invention the numeral 10 denotes a supporting-table mounted upon side frames 11, 11 and firmly supporting two sewing machines 12—12¹, which may be of any suitable character. The machines 12, 12¹ illustrated in the drawings are known in the art as Singer zig-zag sewing machines. The machines are arranged in alinement with and face one another. The feeding mechanisms (not shown) of the sewing-machines are arranged to feed in the same direction, and this result may be accomplished in a well-known manner by reversing the throw of the feed of one machine. Rearward of the table 10 and rearwards of the sewing machines is mounted in suitable bearings 13, 13 the main drive-shaft 14, which receives its power from a belt 15 connected to an electric motor 16. The drive-shaft 14, adjacent the machine 12 has mounted upon it a toothed wheel 17. The main shaft 18 of the machine 12 is provided with a toothed wheel 19 to receive a belt 20 by which the wheels 17 and 19 are connected and through the medium of which motion is communicated from the drive-shaft 14 for imparting power to the main shaft 18 of the sewing machine 12.

The drive-shaft 14, adjacent the machine 12¹ has mounted upon it a gear 21. A gear 22 has been mounted on a stub shaft 23 and in meshed engagement with the gear 21 so as to rotate in opposite directions. The gear 22 has integrally secured thereto a toothed wheel 17¹. The main shaft 18¹ of the machine 12¹ is provided with a toothed wheel 19¹ to receive a belt 20¹ by which the wheels 17¹ and 19¹ are connected and through the medium of which motion is communicated from the drive-shaft 14 for imparting power to the main shaft 18¹ of the sewing machine 12¹. It is to be noted that the distances between the center lines of the toothed wheels 17 and 19, and 17¹ and 19¹ are identical and that both sewing machines are timed to feed equally in the same direction.

The supporting table 10 comprises angle irons 25 secured to the top of the side frames 11. Rectangular bars 26 fastened to the inner faces of the upright legs of the angle irons 25 form a slideway 27 on which the bases 28 and 28' of the sewing machines rest.

Secured to the upper face of the base 28 of the sewing machine 12 is a rearwardly and downwardly extending bracket 30. The bracket 30 has aperture means 31 at its rear end portion which serves to engage the drive-shaft 14. It will thus be noted by reference to Figure 3, that the sewing machine 12 may be swung rearwardly about the drive-shaft 14 and that during the swinging motion the belt 20 remains in timed relation.

The belt 20 is preferably made of canvas and

has transverse wire projections 32 fixed thereto and meshing with the wheel teeth. The belt is rotatably mounted on the toothed wheels so as to cause the drive-shaft 14 to drive the sewing machine main shaft in timed relation with the main shaft of the other sewing machine.

Secured to the head of the sewing machine 12' is a rearwardly and downwardly extending bracket 35. The bracket 35 has an aperture 36 at its rear end portion which serves to engage the drive-shaft 14. The sewing machine 12' may thus be swung rearwardly about the drive-shaft 14. The bracket 35 supports the stub shaft 23, the wheel 17' and gear 22 and the gear 21 (not shown) on the drive-shaft 14.

As shown in Figures 3 and 4, a latch 49 has been mounted on a pivot 41 and is resiliently pressed by a spring 42 in direction of a rectangular bar 26 in the slide-way 27. As shown in Figure 3, the sewing machine 12 may be swung about the drive-shaft 14 until an angular extension 43 engages the lower face of the bar 26 and prevents any further outward swing of the sewing machine. There has thus been provided spring-pressed means for latching the sewing machine 12 in angular relation with the slideway 27.

As shown in Figures 3 and 4, an extension 45 from the bracket 39 has a roller 46 rotatably mounted therein. It is to be noted that before the sewing machine 12 is swung about the drive shaft 14, the chain 56 is unhooked at its lower end from a hook 85 at the upper end of the pendant plate 57. The roller 46, shown in Figure 3, is designed to engage the upper surface of the horizontal leg of one of the angle irons 25 and transmits the load of the overhanging sewing machine to said angle iron. The roller 46 relieves the drive-shaft 14 of the weight of the overhanging sewing machine, and in actual practice, the overhanging machine may be freely rotated while in the angular position and this is of great importance in the maintenance of the two sewing machines.

The sewing machine 12 has a thread cutting shear 50 fastened to the upper surface of the base, behind the head of the sewing machine. The shear 50 has a blade 51 pivotally mounted in a bracket 52 to swing in a vertical plane. A stationary blade 53 lying flat on the base coacts with the movable blade 51. A lever 54 pivotally mounted in an upright extension of the bracket 52 has one of its ends substantially ball shaped and seating in a slot in the movable blade.

Operating movement of the shear 50 is effected by a chain 56 secured to the free end of the lever and which passes through an aperture in the base 28 and projects downwardly therefrom. At the lower end of the chain 56 is a pendant plate 57 which is in suitable engagement with a bar 58 running parallel with the slideway 27, as best shown in Figure 3.

The bar 58 is secured to a rod 59 which is pivotally mounted to swing about a shaft 60. The shaft 60 is rotatably mounted in bearings 61 secured to the lower face of one of the angle irons 25. A rod 62 extending downwardly from the rod 59 to a foot pedal 63 provides means for actuating the shear 50.

The sewing machine 12' has a shear 65, similar to the shear 50 fastened to the upper surface of the base 28', behind the head of the sewing machine. The shear 65 is a left hand shear as distinguished from the right hand shear 50.

A chain (not shown) passing through an aperture in the base 28' is secured at its upper end to the operating lever of the shear 65 and at its lower end to the bar 58. Both shears are thus operated simultaneously by the foot pedal 63.

It is to be noted that the drive-shaft 14 has an elongated keyway 66 in engagement with a key 67 in the toothed wheel 17. It will thus be seen that the main shaft 18 of the sewing machine 12 is rotatable by the drive-shaft 14 in all its slideable positions.

Figure 6 shows an arcuate shield 70 superposed over the drive-shaft 14. The shield 70 may be supported by angular members 71 secured to one of the angle irons 25. A complementary shield 72 has been slidably mounted over the shield 70. The shield 72 is in practice secured to the slideable sewing machine 12. The shield 72 is flexible, due to its large length from the point of support on said slideable sewing machine. As best shown in Figure 6, the shield 72 is secured to the slideable sewing machine 12 by a connecting member 90 well known in the art. The two shield sections are thus relatively shifted automatically with the relative movement between the sewing machines.

Two edge guides 73, 73', have been secured to the bases 28, 28' and serve for receiving the opposite side edges of a strip of fabric which is brought to a roll holder 75 in front of the table 10 rolled up and with both side hems folded. The guides are fastened to the bases adjacent the needles of the sewing machines. The distance between the edge guides corresponds to the overall dimension between the folded hems of the strip of fabric.

When the full length of the strip of fabric has been hemmed, the operator actuates the foot treadle 63 and the two thread-cutting shears 50 and 65 cut both threads simultaneously.

A foot treadle 76 has a treadle rod 77 extending upwardly to a lever 78 which operates a clutch (not shown) in the electric motor 16 and serves for starting and stopping the drive-shaft and both sewing machines. The drive-shaft is driven from the motor 16 by the belt 15 passing over pulleys 79 and 80.

As best shown in Figure 3, the slideable sewing machine 12 has a shaft 81 rotatably mounted in bearings 82, 82 secured to the base 28. A gear 83 is secured to the shaft 81 and meshes with a rack gear 84 secured to the front face of one of the angle irons 25. A handwheel 85 secured to the outer end of the shaft 81 serves for rotating the shaft and thereby causing slideable motion of the sewing machine 12 on the slideway 27 so as to accommodate strips of fabric of different dimensions between the hemmed side edges.

I claim:

1. In a machine of the character described, comprising a table having a slideway and two sewing machines relatively slideable on said slideway and adapted to feed in the same direction, said sewing machines having main shafts above said slideway, a drive-shaft rotatably mounted on said table rearwards of said sewing machines, said drive-shaft having a key lengthwise thereof, a bracket extending from each of said machines, said brackets being respectively fixed to said machines and having means for supporting said drive-shaft, whereby each of said machines may be swung above said slideway for bringing the normally concealed mechanism below the sewing machine base into fully accessible position, a gear

operatively associated with said drive-shaft, a gear secured to said sewing machine main shaft, a fabric belt having spaced metallic projections fixed thereto and meshing with the teeth of the gear wheels mounted on said sewing machine shafts and said drive shaft and forming a belt drive externally of said sewing machine, said external belt drive being operatively connected during said swinging motion and one of said machines being slidable relative to said drive-shaft jointly with its coacting belt drive, said sewing machines having work supporting bases, said drive shaft being mounted below the level of said work supporting bases, said drive shaft being shielded on three sides and comprising a shield superposed over said drive shaft, said shield comprising complementary relatively slidable sections, said sections being shifted automatically with the relative movement between said sewing machines, and a rack-bar fixed to the front face of said slideway with its teeth on its upper side, a shaft rotatably mounted on top of the work supporting base of one of said sewing machines and having a gear secured thereto and in engagement with said teeth, and means for rotating said gear and causing said mentioned sewing machine to travel along said slideway, said slideway having a horizontal surface at the rear thereof, said bracket having a roller rotatably mounted at its lower end and adapted for engagement with said surface in the overhanging position of said sewing machine, for relieving said drive shaft from supporting the weight of said sewing machine and permitting free rotation of said drive shaft.

2. In a machine of the character described, comprising a table having a slideway and two sewing machines mounted in spaced relation on said slideway and adapted to feed in the same direction, said sewing machines having main shafts above said slideway, a drive-shaft rotatably mounted on said table rearwards of said sewing machines, one of said machines being slidable on said slideway, a portion of said drive-shaft rearwards of said slidable machine having a key lengthwise thereof, a bracket extending from each of said machines and having a bearing fixed to the upper surface of the sewing machine base and in engagement with said drive-shaft, whereby each of said machines may be swung above said slideway for bringing the normally concealed mechanism below the sewing machine base into fully accessible position, a toothed wheel mounted on and operatively associated with said drive-shaft, a toothed wheel secured to said sewing machine main shaft, a fabric belt having spaced metallic projections fixed thereto and meshing with the teeth of the gear wheels mounted on said sewing machine shafts and said drive shaft and forming a belt drive externally of said sewing machine and superposed over said table, said superposed belt drive being operatively connected during said swinging motion and said slidable machine being slidable relative to said drive-shaft jointly with its coacting belt drive, said sewing machines having work supporting bases, said drive shaft being mounted below the level of said work supporting bases, said drive shaft being shielded on three sides and comprising a shield superposed over said drive shaft, said shield comprising complementary relatively slidable sections, said sections being shifted automatically with the relative movement between said sewing machines, and a rack-bar fixed to the front face of said slideway with its teeth on its upper side, a shaft rotatably mounted on top of the work supporting base of one of said sewing machines and having a gear secured thereto and in engagement with said teeth, and means for rotating said gear and causing said mentioned sewing machine to travel along said slideway, said slideway having a horizontal surface at the rear thereof, said bracket having a roller rotatably mounted at its lower end and adapted for engagement with said surface in the overhanging position of said sewing machine, for relieving said drive shaft from supporting the weight of said sewing machine and permitting free rotation of said drive shaft.

5 being shifted automatically with the relative movement between said sewing machines, and a rack-bar fixed to the front face of said slideway with its teeth on its upper side, a shaft rotatably mounted on top of the work supporting base of one of said sewing machines and having a gear secured thereto and in engagement with said teeth, and means for rotating said gear and causing said mentioned sewing machine to travel along said slideway, said slideway having a horizontal surface at the rear thereof, said bracket having a roller rotatably mounted at its lower end and adapted for engagement with said surface in the overhanging position of said sewing machine, for relieving said drive shaft from supporting the weight of said sewing machine and permitting free rotation of said drive shaft.

10 3. In a double-hemming machine comprising a table having a slideway and two sewing machines mounted on said slideway to face each other and being adapted to feed in the same direction, a drive shaft co-extensive with said slideway and being rotatably mounted rearwards of said slideway, one of said machines being slidable on said slideway, a portion of said drive-shaft rearwards of said slidable machine having an elongated keyway therein, a bracket fixed to the upper surface of the sewing machine base and extending from each of said machines rearwardly thereof and being in engagement with said drive shaft for mounting said sewing machines in pivotal relation with said drive-shaft, whereby each of said machines may be swung rearwardly into angular relation with said slideway for bringing the normally concealed mechanism below the sewing machine base into fully accessible position, spring-pressed means for latching said machines in said angular position, said sewing machines having main shafts above said slideway, toothed wheels mounted in operatively associated relation with said drive-shaft, toothed wheels secured to said sewing machine main shafts, belts having means for engaging with said toothed wheels and forming timed belt drives superposed over said table, said superposed belt drives remaining operatively connected in said timed relation during said swinging motion, said sewing machines having work supporting bases, said drive shaft being mounted below the level of said work supporting bases, said drive shaft being shielded on three sides and comprising a shield superposed over said drive shaft, said shield comprising complementary relatively slidable sections, said sections being shifted automatically with the relative movement between said sewing machines, and a rack-bar fixed to the front face of said slideway with its teeth on its upper side, a shaft rotatably mounted on top of the work supporting base of one of said sewing machines and having a gear secured thereto and in engagement with said teeth, and means for rotating said gear and causing said mentioned sewing machine to travel along said slideway, said slideway having a horizontal surface at the rear thereof, said bracket having a roller rotatably mounted at its lower end and adapted for engagement with said surface in the overhanging position of said sewing machine, for relieving said drive shaft from supporting the weight of said sewing machine and permitting free rotation of said drive shaft.

15 20 25 30 35 40 45 50 55 60 65 70 JOSEPH GALKIN.
